LAPPING MACHINE

Frederick H. Markwick and Louis F. Pooch, Dayton, Ohio, assignors to The Sheffield Gage Corporation, Dayton, Ohio, a corporation of Ohio

Application July 5, 1935, Serial No. 29,794

14 Claims. (Cl. 51—119)

This invention relates to lapping machines.

One of the principal objects of the invention is the provision of a lapping machine of simple construction that is readily adjustable for operation on work pieces within a wide range of size variation.

Another object of the invention is the provision of such a lapping machine upon which a single workpiece may be quickly and accurately lapped.

Another object of the invention is the provision of a lapping machine having a flat rotatable lapping disk that is adjustably movable to different paths of travel for coordinated movement with a particular workpiece whereby an improved lapping action is obtained and the lap face is maintained flat for an extended period of usefulness.

Another object resides in the method of lapping a workpiece of circular cross section that is rotated on its own axis by engagement with a rotating lapping surface, and is additionally moved with respect to the lapping surface so that the zone of contact is substantially the entire lapping surface.

A further object of the invention is the provision of a lapping machine having a work support of such character that the workpiece, while securely held, is free to move into proper operating relationship with the lap face.

Other objects and advantages of the invention will be apparent from the following description, the accompanying drawings and the appended claims.

In the drawings, which disclose a preferred embodiment of the invention:

Fig. 1 is a plan view of the lapping machine constructed in accordance with the present invention;

Fig. 2 is a transverse vertical sectional view taken on the line 2—2 of Fig. 1;

Fig. 3 is an enlarged fragmentary view of a portion of the work support;

Fig. 4 is a sectional view as indicated by the line 4—4 of Fig. 1;

Fig. 5 is an enlarged fragmentary view of a portion of Fig. 4; and

Fig. 6 is a fragmentary view showing a modified form of lapping disk.

In the drawings, in which like characters of reference designate like parts throughout the several views thereof the lapping machine is illustrated as comprising a bed 10 having suitable supporting legs 11 and 12. Toward one end of the bed is mounted a head 13 that supports a lapping member, shown as a disk 14, and toward

the opposite end of the bed is mounted a work support that is designated generally by the numeral 16.

The mounting for the lapping disk is shown as comprising a member 18 that is fixedly attached to the bed 10 and has spaced upstanding arms 19 incorporating bearings 20 for free rotation of a spindle 21. The end of the spindle extending toward the center of the machine projects beyond its bearing 20 for attachment of the lapping disk. Driving means are provided for the lapping disk in the form of a stepped cone pulley 23 which is fixedly mounted on the spindle intermediate the arms 19 and is adapted to carry a belt connecting to a suitable source of power.

That portion of the spindle to which the lapping disk is attached terminates in an enlarged end 25 having a flat end face 26 against which the lapping disk is adapted to rest. The face 26 is accurately machined to afford a flat surface that is perpendicular to the spindle axis. A slot 27 is provided in the end piece 25 and extends across the end face 26 on a diameter thereof. This slot is widened adjacent its bottom portion as indicated at 28 for reception of the head 29 of a threaded member 30 that attaches the disk 14 to the spindle. The member 30 is adjustably slidable in the slot and may be fixedly held at any desired position therein.

The lapping disk 14, which is preferably made of cast iron or some such material that is suitable for use as a lap, has a circular peripheral edge 32 and parallel flat end faces; the end face 33 lying in surface contact with the face 26 of the part 25 and the opposite face 34 serving as the lapping face with which a workpiece is engaged during the lapping operation. The disk has a central circular opening 35 therein which, toward the lap face 34, is widened into an annular recess as indicated at 36. A sleeve 37, which is receivable on the member 30, serves as a bearing for the lapping disk. One end of the sleeve has a projecting flange 38 which overlies the disk opening 35 within the recess and serves to hold the disk against the plate 25. A nut 40 which engages the member 30, serves to hold the sleeve in clamped engagement on the end face of the part 25. As shown, the recess 36 is of sufficient depth to accommodate the projecting parts of the attaching means below the plane of the lap face 34. The proportioning of the sleeve parts is such that the disk 14 may rotate with respect to the spindle upon which it is mounted. The disk 14 has a running fit on the sleeve. The sleeve length under the flange, although such as

50

55

55

to hold the disk in surface engagement with the end face 26, affords sufficient freedom that the disk may rotate independently of the spindle.

The work support 16 is shown as comprising 5 relatively movable interfitting plates 40 and 41 of which the plate 40 is fixedly mounted to the bed 10 while the plate 41 has adjustably mounted thereon a supporting structure for holding a workpiece in contact with the lap face and for 10 moving the workpiece with respect to the lap face while in operating engagement. The interconnection of the parts 40 and 41 is in the form of interlocking ways common to machine tool practice and as indicated at 42. The ways stand so 15 that the path of travel of the movable part is transverse to the spindle axis. Adjustably mounted on the movable plate 41 is a block 44 that is provided with interfitting ways 45 slidably engaging and supporting a carriage 46 for 20 adjusting movement in the direction of the spindle axis. As shown, attachment of the block 44 to the movable plate 41 is by means of screws 48 that extend through curved slots 49 in the block 44 and threadedly engage the plate 41. 25 The slots 49 are curved on a radius as defined by an imaginary center existing at the midpoint of the screws 48. The slots are of sufficient length to permit a slight amount of angular movement of the block 44.

30 On the block 44 intermediate the ways 45 is an upwardly extending projection 50 which is threaded to receive a screw 51 that is rotatably carried by the carriage 46 as indicated at 52. The screw 51 has fixed to it a crank 53 for rotation thereof whereby the carriage may be moved 35 with respect to the block in the direction of the spindle axis. The carriage 46 has an upwardly extending projection 55 that is provided with an opening 56 extending coaxial with the spindle for attachment of a yoke-shaped member 58 that in turn serves as a support for a work carrying frame. The proportioning of the several parts that make up the work support is such that the center of the carriage opening 40 56 is substantially the same elevation as the axis of rotation of the lap. The yoke shaped member 58 has projecting from one end thereof a stud 57 which is closely received within the carriage opening 56 and is adapted to be held 45 therein by a nut 59. The stud 57 extends oppositely to and stands substantially midway between spaced parallel arms 60. The arms 60, toward their outer ends, each have a threaded opening 61 for reception of a bearing pin 62. 50 The pins have conical ends 63 and are axially aligned to engage and pivotally support a work carrying frame 64.

55 The work carrying frame 64 is arranged as a relatively long bar like portion 65 having inclined guide faces 66 at the opposite sides of one face thereof for accurately mounting a pair of adjustable work holding members 67. At the midpoint of the bar 65 are provided yoke like arms 68 with axially aligned conical depressions 69 which are engaged by the conical ends of the bearing pins 62 for rockably supporting the frame 64. Each of the work holders 67 is provided with a pivot center 72 for pivotally supporting one end of a workpiece and each holder includes 70 means whereby it may be supported by and adjustably fixed to the part 64. As shown, the bar like portion 65 has a slot 73 extending parallel to the inclined faces 66. The slot has an enlarged bottom portion 75 for reception of the head of a clamping member 76 by which the

work holders are held to the frame 64. Each holder 67 has a rockable shaft 77 extending into the lower portion thereof which on the exposed end has an accessible crank arm 79 and on the enclosed end has mounted thereon a cam 80 that is engaged by the loop end 81 of the clamping member 76. The proportioning of the cam, holding member and parts associated therewith is such that in one position of the cam the holding members may be slidably moved along the 10 bar like portion and in another position the holding members are securely locked in place on the bar like portion 65.

The work holders 67, by which the pivot centers are carried, are adjustably mounted so that the 15 spacing of the centers may be altered to accommodate a wide variety of sizes of workpieces. In addition, and for convenience in handling the workpieces, one of the pivot centers is adjustable in its holder 67 so that it may be readily 20 withdrawn when desired in order to afford a greater spacing for attachment or removal of a workpiece from the centers. As shown, the right hand center 72 is slidably mounted within a socket 82 of the holding member 67 and has a 25 stud projection 83 that extends through the end of the socket and has attached thereto a finger piece 85 by which the center 72 may be moved axially against the tension of a spring 84 that is positioned within the socket and bears against 30 the pivot center urging it outwardly toward the opposite center 72. The arrangement of the adjustable holder is such that its center may be held in the withdrawn position when desired. The holder end on the socket axis has a 35 cross slot 86 of such width to receive the thin disk-like finger piece 85. By withdrawing the center and turning the finger piece to a position removed from the slot the center is held in retracted position. Locking means are provided 40 for the right hand center in the form of a screw 88 which is threadedly mounted in the holding member and is adapted upon tightening to securely hold the center in position.

45 There is provision for imparting a reciprocatory motion to the work support. As shown, a shaft 90 is rockably mounted in suitable bearings provided in the legs 11 and 12. This shaft carries a forwardly projecting handle 91 that extends to within convenient reach of the machine operator, and has also an upwardly extending arm 92 having a link connection 93 with an upstanding arm 94 which is pivotally mounted at 95 on the machine leg 12. The upper end of the arm 94 has pivotally connected to it at 96 a link 97 which is pivotally connected at 98 to the movable plate 41. Oscillation of the handle 91 produces a reciprocatory movement of the work support.

60 Workpieces of the character that are subjected to a lapping operation have some provision for mounting them between centers. That is, they either have accurately aligned conical centers for mounting on the supporting centers 72, or they have a central opening therethrough whereby they may be mounted on a suitable arbor which in turn may be mounted on the centers 72. In any event the workpieces are so arranged that they may be carried between the centers 72 in such a manner that the surface that is to 65 be lapped is concentric to the axis of rotation of the workpiece. In Fig. 1 the workpiece that is illustrated in dotted outline comprises a cylindrical plug 100 which is shown carried by an arbor 101 that is mounted on the centers 72. 70 75

As has been pointed out above, the machine is readily adjustable to accommodate workpieces within a wide range of size variation. These pieces may be shorter or longer than the one illustrated and the great majority of them will be considerably shorter than the radial length of the lap face so that in any one position of contact with the lap face only a part of the radial length of the face will be engaged. The abrading action of the lapping operation removes metal from the lap face as well as from the workpiece. A lap, to provide a desired lapping operation, must remain flat. There is provision in the machine whereby the workpiece is caused to traverse a path with respect to the lap face such that substantially the entire face of the lap contacts with the workpiece so that any wear on the lapping face as a result of the lapping operation is uniform and as a result the face remains flat. This desirable feature of uniform wear is obtained by provision of a reciprocatory work support which may be reciprocated during the lapping operation, and by provision of an adjustable eccentric mounting for the lapping disk such that it traverses an eccentric path during rotation. In addition to this there is means provided for moving the lapping disk with respect to its supporting spindle so that the driving relationship of these parts is intermittently changed during use.

As mentioned above, the stud 30 that serves as an attaching means between the lapping disk and its support is carried within a transverse groove 27. The provision of this slotted engagement enables the operator to provide any desired degree of eccentric travel in the lapping disk. As is shown in Fig. 2, the center of rotation of the disk is indicated at 102 and is eccentrically related to the center of rotation of the spindle as indicated by the numeral 103. This association of parts results in a planetary motion being imparted to the disk. Rotation of the disk on the spindle or the change in related positioning of the disk with respect to the spindle occurs as a result of frictional drag produced by contact of the workpiece or by provision of means such as a friction brake 104 which is shown carried by an arm 105 extending from the bed 10 to position the brake so that it may contact with the peripheral edge 32 of the lapping disk. The brake comprises a threaded shaft portion 106 that threadedly engages the bracket and which has on one end thereof a cross pin 107 by which it may be conveniently adjusted. The opposite end of the member 106 is socketed at 108 for reception of a block of some resilient substance such as leather which will frictionally engage the periphery of the lapping disk during its rotation and will momentarily stop the disk or will at least impart some rotational movement of the disk with respect to its spindle. The brake is adjustable so that the desired contacting engagement may be maintained for different degrees of eccentric positioning of the lapping disk and so that, when desired, the brake may be withdrawn entirely from contacting engagement. Referring further to the rotatable mounting of the lapping disk, as has been pointed out, the fit of the pivot sleeve 37 within the disk center is such as to hold the disk in surface contact with the end face of the spindle and, although sufficiently loose to permit relative movement, it is likewise sufficiently tight to avoid objectionable shake or vibration. The disk is quite heavy and, although rotatably mounted,

there is sufficient friction between the disk and its support to cause it to revolve upon rotation of the spindle. Also, because of this driving relationship, but little resistance is required to cause relative movement between the disk and its spindle. This desirable relative movement that provides for full coverage of the disk surface and resulting uniform wear may occur only as a result of contacting engagement of the workpiece with the disk and without use of the friction brake. During the lapping operation the workpiece bears but lightly against the lapping disk and is readily adjusted to a desired engaging relationship by adjustment of the carriage screw 51. Even though the frictional engagement is but a light contact there is sufficient friction between the engaging parts which is effective, particularly when the workpiece engages the disk adjacent the periphery thereof, to produce some relative movement of the disk. This may be a very small amount but, as the workpiece is continually sweeping back and forth across the lapping face, the continued repetition of this small change of movement is sufficient to provide the desired action in the disk. In the case of very small workpieces or workpieces having but a limited engagement with the lap face there may not be sufficient frictional drag to move the disk, in which event the friction brake may be resorted to as a means of altering the disk positioning. Here also the brake may be adjusted so that but a very small relative movement is imparted for each revolution of the disk. However as this occurs for each turn of the disk the wear on the disk is made uniform.

Although the work support is of such construction as to provide a substantial and rigid support of the workpiece such that objectionable shake or vibration is avoided, it is likewise so constructed to provide a movable support for the workpiece so that the workpiece may freely assume a proper operating relationship with the lap face. The work carrying frame 64 is free to swing on its pivot centers 63 so that regardless of whether the workpiece has a cylindrical or tapering peripheral face it may readily move to a positioning such that the workpiece properly engages the lap face. Friction means are provided between the frame 64 and its supporting structure to prevent too much freedom of movement at this point. As shown, the yoke arms 60 have transverse passages therethrough for reception of contact balls 110 that are urged into contacting engagement with the arms 68 through pressure exerted by a spring 111 that is compressed between the ball 110 and a threaded plug 112. The tension afforded by the springs 111 is only sufficient to overcome an objectionable freedom of movement of the frame 64. Free rotation of the workpiece on its centers is assured by provision of the locking screw 88 which permits the centers to be positioned at a desired spacing to thus avoid an objectionable tensioning to these parts which might result from the tensioning of the spring 84.

Unusually long workpieces are readily accommodated in this machine by arranging the machine to permit the application of a lap of increased diameter. As such operation may be required but seldom the large diameter lap is constructed as an attachment which may be readily applied to the lap normally used and forming a part of the machine. Such a lap is illustrated in Fig. 6 and is shown as a disk like

member 115 having opposite parallel faces of which the face 116 lies in surface contact with the lap face 34 and the opposite face 117 is then utilized as the lapping face. This disk is mounted through provision of a central circular passage 118 that receives a screw 119 which threadedly engages the stud 30. An enlarged recess 120 in the lap face accommodates the head 121 of the holding screw.

10 Through provision of this machine an operator is enabled to quickly and accurately provide a superior lapped surface on a workpiece such, for example, as a gage plug. The machine is flexible in that it is provided with a sufficient 15 range of adjustment to readily accommodate plugs within a wide range of size variation and further, it is so arranged that either cylindrical or tapered plugs may be handled. It is further pointed out that as no special adjustments are required other than an adjustment of the holding 20 device a single workpiece of a given size may be handled within a unit of time practically no longer than the unit time for a plurality of pieces of the same size. As the carriage travel is under 25 control of the operator so that the work piece may be caused to sweep the full width of the lap face it may not be necessary to change the degree of eccentricity of the lap face except to handle widely differing work pieces. A single lap 30 may be utilized for any plug that may be accommodated and, as mentioned above, in the case of unusually long plugs an auxiliary lapping disk may be readily attached. Because of the irregular and constantly changed motion of the disk 35 with respect to the workpiece uniform wear on the lapping face is afforded and, in addition, a superior and highly polished surface is provided on the workpiece.

While the method herein described, and the 40 form of apparatus for carrying this method into effect, constitute preferred embodiments of the invention, it is to be understood that the invention is not limited to this precise method and form of apparatus, and that changes may be 45 made in either without departing from the scope of the invention which is defined in the appended claims.

What is claimed is:

1. A lapping machine comprising a rotatable 50 lapping member having a flat lapping face, drive means effective on the lapping member to impart a driving force thereto that is of substantially uniform value and is small enough in comparison to the retarding effect of a work piece held there- 55 against to produce change in the rotational speed of the lapping member by varying the positioning of the work piece with respect to the axis of rotation of the lapping member, means for holding a workpiece in engagement with said lapping member, and means for moving the work piece across the face of the lapping member to inde- 60 terminately vary the driving relationship be- 65 tween the drive means and the lapping member.
2. A lapping machine comprising a lapping 65 member comprising a circular disk having a flat lapping face and having a mounting portion at the center thereof, means for rotatably holding a workpiece having a curved surface of revolution in engagement with the lapping flat face of the 70 member, means for moving the holding means across the face of the lapping member, support- 75 ing means for the lapping member comprising a rotatable spindle, means on the spindle slidably transversely of the spindle axis and rotatably supporting the mounting portion of the lapping

member in frictional driving engagement, and means to adjustably attach said slidably means to the spindle at varying degrees of eccentricity of the lapping member mounting portion with respect to the spindle axis of rotation.

3. A lapping machine comprising a lapping member comprising a circular disk having parallel flat faces and a central opening for mounting thereof, means for holding a workpiece in engagement with the lapping member, supporting 10 means for the lapping member comprising a rotatable spindle, said spindle having an end portion extending transversely of the spindle axis and terminating in a flat face extending perpendicular to the spindle axis, and mounting means 15 rotatably carrying the lapping member by engagement with the central opening thereof and having an interfitting connection with the spindle for support of the lapping member on the spindle with one face of the lapping member and the end 20 face of the spindle in surface contact, said mounting means being adjustable on the spindle end portion for adjustably varying the eccentric relationship of the lapping member center with respect to the spindle axis of rotation.

4. A lapping machine comprising a circular disk-like lapping member having flat parallel faces of which one face is the lapping face, said lapping member having a central opening there- 30 through terminating in an enlarged recess at the lapping face, means for holding a workpiece in engagement with the lapping member, a rotatable spindle for the lapping member, a sleeve extending through the lapping member central opening and having an end flange overlying the central 35 opening at the recess, a bolt extending through said sleeve and adjustably receivable on said spindle and adapted upon tightening to fixedly hold the sleeve with respect to the spindle for adjustably positioning the lapping member at 40 varying degrees of eccentricity with respect to the spindle axis, said sleeve flange and bolt lying within the lapping member recess beneath the plane of the lapping face.

5. A lapping machine comprising a lapping 45 member having a flat lapping face, means for holding a workpiece in engagement with the lapping member, supporting means for the lapping member comprising a rotatable spindle, means rotatably mounting the lapping member on the 50 spindle with the lapping member flat face extending perpendicularly to the spindle axis, and friction means intermittently operable during a lapping operation to move the lapping member with respect to the spindle.

6. A lapping machine comprising a lapping member having a lapping face, means for holding a workpiece in engagement with the lapping member, supporting means for the lapping member comprising a rotatable spindle, means ro- 60 tatably mounting the lapping member on the spindle with the lapping face extending perpendicularly to the spindle, and means intermit- 65 tently engaging the lapping member upon rotation of the spindle to impart relative movement to the lapping member with respect to the spindle.

7. A lapping machine comprising a base, a lapping member comprising a circular disk-like member having a flat lapping face, means on the base for holding a workpiece in engagement with 70 the lapping member, supporting means on the base for the lapping member comprising a ro- 75 tatable spindle, means rotatably mounting the lapping member on the spindle with the lapping member flat face extending perpendicularly to 75

the spindle, and means adjustably supported from the lapping machine to intermittently contact the lapping member in frictional engagement upon rotation of the spindle for momentarily holding the lapping member.

8. A lapping machine comprising a rotatable spindle, a lapping member eccentrically mounted thereon and having driving engagement therewith only by virtue of frictional contact, said lapping member having a lapping face extending perpendicularly to the spindle axis, supporting means for holding a workpiece in engagement with the lapping member, said supporting means comprising a frame having axially related points of support defining an axis of rotation for the workpiece, means rockably supporting said frame for free turning movement on an axis extending transversely through the axis of rotation of the workpiece and extending transversely of the spindle axis, and means for reciprocating the frame in the direction of the plane of the lapping member face for traverse of a supported workpiece across the lapping face towards and away from the axis of rotation of the spindle.

9. A lapping machine comprising a rotatable spindle having a lapping member providing a lapping face extending perpendicularly to the spindle axis, supporting means for holding a workpiece in engagement with the lapping member comprising a rockable frame having a bar-like portion, spaced members adjustably movable on the bar-like portion, said members having axially aligned pivot members defining an axis of rotation for a workpiece, said bar-like portion having members extending oppositely from each side adjacent the midpoint thereof and curving toward one another to form a U-shaped yoke of which the member ends continue beyond the axis defined by the axially related pivot members, a movable carriage for the frame comprising yoke-like arms encircling the members of the bar-like portion, and axially related bearing means connecting the yoke-like arms of the frame and carriage on a line extending through the axis of rotation of the pivot members and extending transversely to said axis of rotation and to the axis of rotation of the spindle.

10. A lapping machine comprising a lapping member having a lapping face, a rotatable spindle supporting said member and frictionally engaged therewith to provide rotation of the lapping member on the spindle during operation, means for rotating said spindle, a work holder having centering means for rotatably supporting a workpiece for movement about an axis extending angularly to the axis of rotation of the spindle, a support carrying said work holder for movement about an axis extending substantially transverse of the work axis, and means for moving the work support so that all of the work which engages the lapping face moves toward the axis of rotation of the spindle or moves away from the axis of rotation of the spindle to indeterminately vary the driving relationship between the spindle and the lapping member.

11. A lapping machine comprising a lapping member supported for free turning movement with respect to a fixed axis, said lapping mem-

ber having a lapping face, rotatable means frictionally engaging said lapping member and adapted to impart a rotative driving force thereto by virtue of frictional contact therewith which is small enough to produce a substantial frictional slip of the lapping member with respect to the rotatable means during operation, and means for holding a curved surface of revolution in rolling contact with the face of the lapping member for rotation thereby and for moving the surface of revolution thereacross as a means of influencing the driving effort acting between the rotatable means and the lapping member to influence the rotation of the lapping member and vary the rotational relationship between the surface of revolution and the lapping member.

12. A machine of the character described comprising a member having a work engaging lapping face, a rotatable spindle supporting said lapping member eccentrically of the axis of rotation of the spindle and frictionally engaged with the lapping member to provide relative rotation during operation, means for rotating the spindle, a work support having centering means for rotatably supporting the work for movement about an axis extending angularly to the axis of rotation of the spindle, and means for moving the work support to move the work across the face of the lapping member and indeterminately vary the driving relationship between the spindle and the lapping member.

13. A lapping machine comprising a lapping member having a flat lapping face, means for rotatably holding a workpiece having a curved surface of revolution in engagement with the flat face of the lapping member, supporting means for the lapping member comprising a rotatable spindle the axis of which is angularly related to the axis of rotation of the workpiece, means eccentrically and rotatably mounting the lapping member on the spindle with the lapping member's flat face extending perpendicularly to the spindle axis and providing driving relationship between the spindle and the lapping member effective only through frictional contact for variation of the driving relationship between the spindle and the lapping member during operation, and means for moving the workpiece across the face of the lapping member.

14. A lapping machine comprising a lapping member having a lapping face, means for rotatably holding a workpiece having a curved surface of revolution in engagement with the lapping face, supporting means for the lapping member comprising a rotatable spindle the axis of rotation of which is angularly related to the axis of rotation of the workpiece, means adjustably attachable to the spindle at varying amounts of eccentricity with respect to the spindle axis and rotatably mounting the lapping member with the lapping face extending transversely of the spindle axis and providing driving relationship between the spindle and the lapping member effective only through frictional contact such that relative rotational movement of the spindle and lapping member occurs during operation, and means for moving the workpiece across the face of the lapping member.

FREDERICK H. MARKWICK.
